DENTAL INSTRUMENT

John F. McMath, Oakland, Calif.

Application September 5, 1936, Serial No. 99,613

11 Claims. (Cl. 15—167)

My invention relates to dental instruments, and more particularly to tooth cleaning tools, such as tooth brushes, having oscillatable heads. This application is a continuation-in-part of my c⁵ o¹⁰ pending application, Serial No. 703,704, filed Dec. 23, 1933.

It is desirable for efficacious operation of a dental instrument, such as a tooth brush, in the mouth of a person, that the tool or brush have oscillatory or relative pivotal movement with respect to the handle upon which it is mounted. This is so because, as the relative movement occurs, a rack and pinion-like effect occurs between the bristles of the tooth brush and the interstices or spaces between the teeth, to cause the bristles to enter such spaces and thus effect thorough cleansing in a very vital spot. With the conventional type of tooth brush, where the handle is rigidly fixed to the head of the brush, the ends of the bristles merely ride over the spaces or interstices between the teeth, resulting in lack of cleaning efficiency.

Pivotal or oscillatory mountings for the tool on the handle have been employed, as is taught in the patents to Newlon et al (Br.) No. 17,808 of 1915; Weis No. 1,706,555; Czencz No. 1,776,312; and my own prior Patent No. 1,968,303.

However, with respect to pivotal instruments having oscillatable tools, there existed the problem of providing a construction which would avoid pinching of delicate mouth tissues or membranes as relative movement between the handle and the tool occurred, and of providing a pivotal connecting means between the handle and the tool, which would not result in unduly increasing the external dimensions of the tool. Obviously, with any ordinary type of movable tool and handle connection, the mouth membranes will be caught and pinched, thus rendering impractical such advantageous arrangement. As for the problem of providing a small mounting of the character related, which does not require substantial increase in size of any given size tooth brush or tool, it is apparent that the mouth is limited as to space. One, therefore, could not with comfort employ a large tool. In addition, the problem existed of providing a mounting of the character related, in which no metal forming part of the mounting, could come in contact with the teeth, which would be undesirable.

My invention is designed to obviate the above described difficulties in constructions of the character related, and has as its objects, among others, the provision of improved:

1. Means for connecting the dental tool for relative movement with respect to the handle therefor, in a manner to preclude pinching of mouth membranes as such relative movement occurs;

2. Connecting means, of the character related, arranged within substantially the normal dimensions of the tool, especially the side extremities or widthwise dimensions of the tool, to thereby afford complete and normal usage of the tool in the mouth; and

3. Detachable connection between the tool and the handle therefor, to enable facile replacement of a worn tool or brush by a new one when so desired.

Other objects of the invention will become apparent from a perusal of the following description thereof:

In general, the dental instrument of my invention comprises a tool including a head having edge extremities, namely opposite end edges, and opposite side edges joined to the end edges. Suitable cleaning means, such as the usual brush bristles, or any other suitable means such as a resilient cleaning sponge or pad, is secured to one face or surface of the head. The handle for the instrument has a portion extending past one end extremity or edge of the tool, and is connected to the tool, between the opposite side edges, for relative pivotal movement with respect thereto, so as to enable oscillatory movement of the tool with reference to the handle.

Means, confined substantially within the area bounded by the edge extremities of the tool, is provided to limit oscillatory movement of the tool with respect to the handle; and the parts are so connected adjacent the end edge or extremity past which the handle extends, as to provide shield means for precluding pinching of mouth membranes within the limits of the relative movement permitted. This is primarily accomplished by having at least some portions of the tool and the handle adjacent the extremity referred to, always in cooperating overlapping relationship within the limits of movement allowed, so as to leave no opening in which membranes can be caught as the relative movement occurs. Inasmuch as the connecting and motion limiting means between the tool and the handle, are confined substantially within the area bounded by the edge extremities of the tool, particularly the side edge extremities which determine the widthwise dimensions of the tool, increase, in the effective size of the tool is obviated, and the tool can be used in the mouth with comfort.

Reference will now be made to the drawings for a more detailed description of the invention:

Fig. 1 is a plan perspective view of tooth brush constructed in accordance with my invention.

5 Fig. 2 is a sectional elevation of the brush shown in Fig. 1.

Fig. 3 is a bottom view of the brush head, namely a view looking toward the bristle face of the brush head.

10 Fig. 4 is a side view of a tooth brush of modified design, the brush head being shown in section.

Fig. 5 is a transverse sectional view of the brush taken on the line 5—5 of Fig. 4.

15 Fig. 6 is a perspective view of another embodiment of the invention, illustrating the tool and the handle detached from each other. A portion of the handle is broken away to shorten the view.

Fig. 7 is a longitudinal sectional view through 20 the tool taken in a plane indicated by line 7—7 in Fig. 6, illustrating the tool and the handle connected together.

Fig. 8 is a plan view of a further modified form 25 of the invention.

Fig. 9 is a longitudinal sectional view taken in a plane indicated by line 9—9 in Fig. 8.

Fig. 10 is plan view of another form of device.

Fig. 10a is an end elevation looking in the 30 direction of arrow 10a in Fig. 10; the handle being shown in section.

Fig. 11 is a longitudinal sectional view taken in a plane indicated by line 11—11 in Fig. 10.

Fig. 12 is a plan view of a still further embodiment of the invention.

35 Fig. 13 is a longitudinal section taken in a plane indicated by line 13—13 in Fig. 12.

Fig. 14 is a fragmentary longitudinal sectional view, through the preferred form of instrument.

40 Fig. 15 is an under elevational view looking in the direction of arrow 15 in Fig. 14; the tool head in Fig. 15 being shown in phantom lines.

45 As illustrated in Figs. 1 through 3 of the drawings, the connection of my invention as applied to a tooth brush comprises a tool including brush head 6 formed with a back surface or face 7; to the opposite face of the head are secured cleaning means such as brush bristles 8. Provided in the head 6 and longitudinally extending inwardly from one end or edge extremity 11 thereof, between the opposite side edge extremities joining such end extremity, is a slot or recess 12 which is 50 arranged to receive an extension piece or tang 13 forming a portion of brush handle 16. The tang portion of the handle 16 is thus confined between the widthwise dimensions or side edges of the tool. Slot 12 is open at both the back and the front of head 6 or in other words at each of the opposite surfaces or faces of the head; and the extension 13 of the brush handle is of a width substantially equal to the width of slot or recess 12. Means for pivotally connecting the tool head and the handle includes a pin 17 extending transversely through the head, and engaging the extension piece 13 within the slot and adjacent the 55 opposed ends 18 and 21 of the slot and the extension, respectively.

60 The pivotal movement of the head relative to the handle is arranged to be limited, so that some part of the handle extension 13 adjacent the end extremity 11 always is in cooperating overlapping relationship with such extremity, and is shielded in slot 12 adjacent extremity 11. Thus, within the limits of the relative movement permitted, no opening is ever formed between the handle and the head adjacent extremity 11, in

which mouth membranes can be caught. In fact, as may be best seen from Fig. 2, the depth of extension 13 is arranged less than the depth of the brush head, to thereby permit the limited relative oscillation of the head about the extension without causing an appreciable uncovering of the handle extension at all.

65 As a means for limiting oscillation of the head about pin 17 which provides the pivot for the movable connection between the tool and the handle, the upper end portions 22 and 23 of the opposed slot and extension ends 13 and 21, respectively, are arranged to cooperate to provide one stop means for limiting upward movement of handle 16, as is illustrated by the solid line 15 position in Fig. 2. Such portions 22 and 23, in the dotted line position of the handle shown in Fig. 2, are formed so as to be divergently disposed with reference to pin 17, to allow the limited movement of the handle in a counterclockwise 20 direction from the dotted line position to the full line position in Fig. 2. The other stop means for limiting downward movement of the handle, in a clock-wise direction from the solid line to the dotted line position shown in Fig. 2, is provided by the lower portions 26 and 27 which form 25 continuations of portions 22 and 23, respectively.

30 Such portions 26 and 27 slant at a comparatively sharp angle from portions 22 and 23, respectively, toward the open end or extremity of slot or recess 12 and, hence, cooperate with stop portions 22 and 23 to restrict movement of the handle to an extent materially less than 45°, to thereby provide for a portion of the handle adjacent the end edge extremity 11 of the head, at 35 the open end of slot 12, always to work or remain in the slot, as relative movement between the tool and the handle occurs. In effect, some portions of the handle and the head are always in overlapping relationship adjacent extremity 11, and this coupled with the open-ended slot construction in the head, causes the end extremity of the head past which the handle extends, to serve as a shield for the movable portion of the handle. 40 This avoids pinching of delicate mouth tissues or 45 membranes, as the desirable oscillatory movement occurs.

50 In this manner, sufficient amplitude of oscillation is afforded the tool during cleaning of the teeth, to allow effective cleansing in the spaces occurring between the teeth; and the handle will be substantially always in line with the head 6, as exists in known constructions where the brush or tool head is fixed against movement with reference to the handle, to offer no inconvenience in manipulation. With the movable connection between the handle and the brush head and the stop means, made substantially entirely within the confines or edge extremities of the head, it 55 will be understood that no increase in the overall size of the tooth brush is made necessary by such connection, and that, therefore, the use of the tooth brush in the mouth as to mouth opening and length of brush stroke, will be unchanged 60 from that of the usual brush.

65 As shown in Figs. 1 and 2, the face or surface of the head, to which the cleaning means is secured, is convexly curved about the pivotal connection of the head and the handle, and the bristles are arranged with their longitudinal axes generally radially of the connection. As a result, the forces incident on the bristles during the brushing of the teeth upon oscillation of the brush head, will be applied generally longitudi- 70 75

nally of the bristles or along the line of their greatest resistant strength.

In Figs. 4 and 5, a modified form of the construction is shown. In this embodiment, there is substituted for the pin 17, a pair of pin extensions 28 formed preferably as a part of the handle or tang extension 13' and arranged to seat in a recess 29 extending transversely across the upper face of the brush head. Retention of the pin extensions 28 in the recess is effected by means of a spring yoke 31 fitting over the head, and releasably engaging at its ends in depressions 32 formed in the side edge extremities of the head. In this arrangement, the yoke serves as a means for limiting oscillation of the head in one direction. Because of the spring yoke 31, which, as previously stated, is releasably held, the tool may be readily replaced by a new one when the brush bristles become worn from use. Obviously, the tool may have other cleaning means in place of brush bristles 8 secured to the head, such as a cleaning sponge or pad.

In both modifications thus far described, it will be observed that the connection between the tool and the handle is confined substantially within the width-wise dimensions or side edge extremities of the tool. In actuality, such connection is confined substantially within the area bounded by the edge extremities of the tool, namely the opposite end extremities and the opposite side extremities. This avoids increase in effective size of the tool, as exists in prior known constructions wherein the tool is movable relative to the handle and motion limiting means provided. As a result, no inconvenience or discomfort obtains when the tool is used in the mouth. Furthermore, the motion limiting means, which restricts oscillatory movement of the head relative to the handle, serves to maintain at least some parts of the handle and the head at the extremity past which the handle extends, in cooperating overlapping engagement, to thus provide shield means which prevents pinching of mouth membranes as such oscillatory movement occurs.

Figs. 6 and 7 illustrate another embodiment of the invention in which the principles disclosed in Figs. 1 through 5 are employed. In such embodiment, the face or surface 40 of tool head 41 is formed with inwardly extending groove 42 which communicates with recess or slot 43 in the end edge or extremity 44. Such recess is open at both surface 40 of the head and the opposite surface 46 to which the brush bristles 47 are secured, but does not extend inwardly all the way to the central portion of the head as occurs in the modifications of Figs. 1 through 5. It will be noted that recess 43 extends inwardly only to a position adjacent the end of the brush bristles.

Extension or tang portion 48 of tool handle 49, is pivotally connected to the tool to allow limited oscillatory movement of the tool with respect to the handle, in such manner that a projecting portion 51 on the handle extension, always works or lies in recess 43, or in other words overlaps extremity 44. This is accomplished by positioning portion 52 of extension 48 over head 41 above groove 42, and between the side edges or extremities 53 of the head. The pivotal connecting means includes fork 54 pivotally connected to the end of portion 52, and which is adapted to be detachably or removably seated in apertures 56 formed in the head.

Portion 52 is provided with downwardly extending pin member 57 rigidly secured thereto,

and which is adapted to enter aperture 58 between apertures 56. Aperture 58 is of larger diameter than the diameter of pin 57, to thus allow the limited pivotal or oscillatory movement of the tool with respect to the handle. This limited movement, as previously explained, is such as to provide the shield means adjacent the portion of the handle extending past edge extremity 44, to preclude pinching of mouth membranes as the movement occurs. Fig. 7 illustrates in the solid and dotted line positions, the limits of movement of the handle. In the dotted line position of the handle, it will be observed that groove 42 accommodates the under edge of portion 52 which passes over the head between opposite side edges 53.

The modification of Figs. 6 and 7 is desirable because, inasmuch as recess 43 does not extend inwardly to the central portion of the tool but only to the end of bristles 47, the longitudinal rows of bristles may be placed closely together within a minimum width of tool head. Although portion 52 of the handle passes over the head and the overall depth of the tool is, consequently, increased, nevertheless, the pivotal connection between the tool and the handle and the motion limiting means are confined within the area bounded by the side edge extremities of the tool, or in other words between the width-wise dimensions of the tool, to thereby avoid increase in size of such dimensions which is undesirable. The increased depth of the tool, offers no discomfort in manipulation because such increase is on the face of the head opposite the cleaning means face, and the mouth can readily accommodate this.

As with respect to the previously described modifications, the tool can be readily removed from the handle, merely by pulling the handle so that the prongs of fork 54 and the pin 57, leave apertures 56 and 58, respectively; and a new tool can be readily substituted therefor.

Figs. 8 and 9 depict a further modification similar to that illustrated in Figs. 6 and 7, but in which the slot or recess adjacent the end edge or extremity 60 past which handle 61 extends, is omitted. In the construction of Figs. 8 and 9, extremity 60 is formed with a curvature concentric with the pivotal axis 62 of the connection between the handle 61 and the tool; such connection being the same as that described with reference to Figs. 6 and 7. Also, portion 63 of the handle, which always overlaps extremity 60, is formed with a curvature complementary to the curvature of extremity 61, so as to cooperate with such extremity in providing the shield means for preventing formation of an open space in which mouth membranes can be caught as relative movement between the handle and the tool occurs.

The motion limiting means in Figs. 8 and 9 restricts relative movement of the handle with respect to the tool within the full line and dotted line positions of the handle, shown in Fig. 9. Thus, such motion limiting means, as in the previously described modifications, always serves to provide a portion of the head and the handle in shielding cooperation, adjacent the end edge or extremity past which the handle extends.

An additional embodiment of the invention is shown in Figs. 10 through 11, in which the brush bristles themselves serve as the shield means to prevent formation of an open space in which mouth membranes can be caught. Brush bristles 65 extend in longitudinal rows closely adjacent

to both of the opposite end edges or extremities 66 of tool head 67; and the portion 68 of the handle which extends past one end extremity 66, passes through the space between the intermediate rows of bristles. Such portion 68 of the handle is formed with an up-turned end 68' which is pivotally connected to pin 69 removably held in the head; the end 68' entering tapered aperture 70, the sides of which serve to limit motion of the handle with respect to the tool.

Figs. 12 and 13 illustrate a still further form of the invention, in which a resilient shield or pad, preferably of sponge rubber, is provided adjacent the end edge or extremity of the tool, past which the handle extends, to cooperate in preventing pinching of mouth membranes. In such form, the handle 71 and the tool head 72 are pivotally secured for limited oscillatory movement in the manner disclosed in Figs. 6 and 7; and recess 73 is formed in the end edge or extremity 74 past which the handle extends. Shield portion 75 on the handle lies in recess 73 and overlaps edge or extremity 74.

Extremity 74 is formed with a curvature eccentric to the pivotal axis 76; and a rubber pad or insert 77, having a complementary curvature adjacent extremity 74, is formed with a slot in which portion 75 of the handle lies and is pivotally connected to the handle at 78. Because of the complementary eccentric curvatures of extremity 74 and pad 77 adjacent the extremity, the pad will remain engaged with the extremity as relative movement between the tool and handle occurs. This cooperates with the shield means formed by the portion 75 of the handle which overlaps extremity 74, to insure against pinching of mouth membranes as the limited relative movement occurs.

The preferred construction employs a resilient or spring latch connection between the tool and the handle, which enables ready attachment and disconnection between these parts. Such construction is illustrated in Figs. 14 and 15, and comprises head 80 having brush bristles 81 secured, in the usual manner, to face 82 thereof. In the opposite face 83 of the head is formed a longitudinally or axially extending groove 84 which runs inwardly from end extremity or edge 86 of the head and which communicates with recess 87 at such end extremity. Groove 84 and recess 87, as with respect to prior modifications, are located between the opposite side edges of the head, which join end edge 86.

Handle 88 has tang or extension 89 which extends over the head past end edge or extremity 86, and between the opposite side edges of the head, and is of substantially the same width and depth as that of groove 84 to lie completely in the groove in one extreme position of the handle. Extension 89 is adapted for pivotal connection to the tool on pin 91, lying transversely in the head, in a manner to be subsequently explained. As with respect to the modification of Figs. 6 and 7, extension 89 has shield portion 92 which lies in recess 87 and always overlaps extremity 86. An end projection 93 on shield portion 92 extends over the cleaning element face 82 of the head, to provide stop means for engaging such face 82 in another extreme position of the handle. Thus, the handle portion 89 extends over one face 83 of the head and provides stop means for limiting movement of the handle in one direction, as illustrated by the full line position in Fig. 14; and the projection 93 on shield portion 92 of the handle, is adapted to engage the opposite face 82 of

the head for limiting movement of the handle in the opposite direction, as is illustrated by the broken line position in Fig. 14. Pinching of mouth membranes as relative movement between the handle and the tool occurs, is hence avoided in the manner previously described. It will be noted that because groove 84 is adapted to receive extension 89, a compact structure obtains.

The spring latch connection between the handle and the tool will now be described. Extension 89 is hollow inside and open underneath, as can be seen more clearly from Fig. 15. At its far end, it is formed with a bayonet slot or recess 96 in which pivot pin 91 is adapted to be engaged, as shown in Fig. 14. A generally L-shaped leaf 15 spring member 97 is mounted within extension 89, with one leg 98 thereof welded between the sides of projection 93. The other leg of the spring extends longitudinally or axially along handle extension 89, and has a hook portion 99 lying in recess 96. Such hook portion normally engages in turned flanges 101 on extension 89; the flanges 101 thus providing an abutment for the spring which, because of being anchored to projection 93, can be shifted or moved axially along the handle extension, to separate hook 99 from abutment 101.

In connecting the tool and the handle, it is only necessary to first position pin 91 between hook 99 and abutment 101, and press down on the handle while moving it axially in the direction of edge 86, to separate the hook 99 from abutment 101, and thereby cause pin 91 to snap into bayonet slot or recess 96. The spring bearing against pin 91 will then hold the pin securely in the horizontal portion of the bayonet slot, so that during manipulation of the tool in the mouth, it cannot become detached from the handle. Detachment of the tool from the handle can be readily effected in a reverse manner.

In all embodiments of the invention, even though relative movement occurs between the handle and the tool, pinching of mouth membranes at the extremity of the tool past which the handle extends, is avoided. At the same time, the external edge dimensions of the tool, especially the width-wise dimensions, are not increased. Thus, the tool can be employed comfortably in the mouth. As previously related, any suitable cleaning means, instead of brush bristles, can be employed in any of the modifications described.

I claim:

1. A dental instrument comprising a tool including a head having edge extremities, a handle having a portion extending past one extremity and positioned between opposite extremities joining said one extremity, and means confined substantially between said opposite extremities for connecting said tool and said handle for limited relative pivotal movement therebetween, the limits of movement being such as to preclude reversal of the position of said handle and to cause said handle portion to extend always past said one extremity, the handle having a part adjacent said one extremity to cooperate with such extremity in providing shield means for precluding pinching of mouth membranes within the limits of relative movement between said handle and said tool.

2. A dental instrument comprising a tool including a head, a handle having a portion extending past an end extremity of said head and positioned between opposite side extremities joining said end extremity, means substantially between said opposite side extremities for connect-

ing said tool and said handle for relative pivotal movement therebetween, and stop means confined substantially between said opposite side extremities for limiting said relative movement, the handle having a part adjacent said end extremity adapted to overlap such extremity within the limits of said relative movement to thereby cooperate with said end extremity in preventing formation of an open space in which mouth membranes can be caught.

3. A dental instrument comprising a tool including a head, a handle having a portion extending past an end extremity of said head and over said head between opposite side extremities joining said end extremity, means substantially between said opposite side extremities for connecting said tool and said handle for relative pivotal movement therebetween, and stop means confined substantially between said opposite side extremities for limiting said relative movement, the handle having a part adjacent said end extremity adapted to overlap such extremity within the limits of said relative movement to thereby cooperate with said end extremity in providing shield means for precluding pinching of mouth membranes.

4. A dental instrument comprising a tool including a head having a recess extending inwardly from an end extremity thereof, a handle having a portion extending past said end extremity and positioned between opposite side extremities joining such end extremity, means substantially between said opposite side extremities for connecting said tool and said handle for relative pivotal movement therebetween, and stop means confined substantially between said opposite side extremities for limiting such relative movement, the handle having a part adjacent said end extremity adapted to lie substantially in said recess and overlap such extremity within the limits of said relative movement.

5. A dental instrument comprising a tool having edge extremities, a handle having a portion extending past one extremity and positioned between opposite extremities joining said one extremity, means confined substantially between such opposite extremities for connecting said tool and said handle for limited relative movement therebetween, and means adjacent said one extremity including a resilient pad for providing a shield to preclude pinching of mouth membranes as such limited relative movement occurs.

6. A dental instrument comprising a tool head having cleaning means secured to a face thereof and a recess extending inwardly from an end extremity thereof between and in the direction of opposite side extremities joining said end extremity and forming the lengthwise extremities of said head, a pin in said head and extending transversely between and normal to said opposite lengthwise extremities, means for detachably connecting said head and said handle for relative free pivotal movement therebetween in a plane normal to said head during working operation of said tool comprising a spring latch connection between said handle and said pin, means confined substantially between said opposite lengthwise extremities for limiting said relative movement within a predetermined range of movement, and shield means adjacent said end extremity for precluding pinching of mouth membranes as such limited relative movement occurs.

7. A dental instrument comprising a tool head

having cleaning means secured to a face thereof and a recess extending inwardly from an end extremity thereof to a position adjacent an end of said cleaning means, a handle having a portion extending past said end extremity over the opposite face of said head and between opposite side extremities joining said end extremity, means substantially between said opposite side extremities for detachably connecting said tool and said handle for relative pivotal movement therebetween, said portion of said handle being engageable with said opposite face of said head to limit said pivotal movement in one direction, a second portion on said handle adapted to lie in said recess and overlap said extremity, and means on said second portion of said handle for engaging said first mentioned face of said head to limit said pivotal movement in an opposite direction.

8. A dental instrument comprising a tool; a handle; and means for detachably connecting said tool and said handle for free relative pivotal movement therebetween within a predetermined range of movement during working operation of said tool comprising a pin in said tool, said handle having a recess in which the pin is engageable, and resilient means adjacent said handle recess and engageable with said pin for maintaining engagement between the pin and the handle.

9. A dental instrument comprising a tool head; a handle; and means for detachably connecting said tool and said handle for free relative pivotal movement therebetween within a predetermined range of movement during working operation of said tool comprising a pin in said head, said handle having a recess in which the pin is engageable, and a spring movable axially along said handle and having a hook in said recess adapted to embrace and hook over said pin.

10. A dental instrument comprising a tool head having an end extremity, a handle extending past said end extremity and positioned between opposite side extremities forming the lengthwise extremities of said head, a pin in said head and extending transversely between and normal to said opposite lengthwise extremities, means for detachably connecting said head and said handle for relative free pivotal movement therebetween in a plane normal to said head during working operation of said tool comprising a spring latch connection between said handle and said pin, means confined substantially between said opposite lengthwise extremities for limiting said relative movement within a predetermined range of movement, and shield means adjacent said end extremity for precluding pinching of mouth membranes as such limited relative movement occurs.

11. A dental instrument comprising a tool having edge extremities, a handle having a portion extending past one extremity and positioned between opposite extremities joining said one extremity, means confined substantially between said opposite extremities for connecting said tool and said handle for free relative movement therebetween in a plane normal to said tool during working operation of said tool, and means substantially between said opposite extremities for confining such relative movement within limits precluding reversal of the position of said handle with respect to said tool to cause said handle to extend always past said one extremity.

JOHN F. McMATH.
